US0D1033627S

(12) **United States Design Patent** (10) **Patent No.:** **US D1,033,627 S**
(45) **Date of Patent:** **** Jul. 2, 2024**

(54) **NASAL IRRIGATOR**

(71) Applicant: **Suzhou Algernon Network Technology Co., Ltd.**, Suzhou (CN)

(72) Inventor: **Xinwei Gu**, Suzhou (CN)

(73) Assignee: **Suzhou Algernon Network Technology Co., Ltd.**, Suzhou (CN)

(**) Term: **15 Years**

(21) Appl. No.: **29/847,066**

(22) Filed: **Jul. 21, 2022**

(51) **LOC (14) Cl.** **24-02**

(57) **CLAIM**

The ornamental design for a nasal irrigator, as shown and described.

DESCRIPTION

FIG. 1 is a front perspective view of a nasal irrigator, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the nasal irrigator, which form no part of the claimed design.

1 Claim, 7 Drawing Sheets
